SWITCH CONTROL MECHANISM

John H. Horman, Tuckahoe, N. Y., assignor, by
mesne assignments, to Smaller War Plants Cor-
poration, New York, N. Y., a corporation of the
United States

Application May 12, 1943, Serial No. 486,681

17 Claims. (Cl. 200—5)

This invention relates to switch control mechanism.

An object of this invention is a control mechanism for a main switch and one or more auxiliary switches of such arrangement that an auxiliary switch can be actuated only after actuation of the main switch.

Another object of the invention is a control mechanism for a main switch and one or more auxiliary switches of such arrangement that return of the main switch to unactuated position automatically effects return of any actuated auxiliary switch to unactuated position.

A further object of the invention is a control mechanism for a main switch and one or more auxiliary switches of such arrangement that with the main switch open all the auxiliary switches are open and no one of them can be closed but that after the main switch is closed any auxiliary switch may be closed and upon opening of the main switch any closed auxiliary switch is automatically opened.

In one embodiment of the invention there is provided a frame movable between a first and a second position together with means for biasing the frame into its first position. The main switch is equipped with means effective upon change of the switch from open to closed condition to move the frame from its first to its second position and upon change from its closed to its open condition to allow return of the frame to its first position. Each auxiliary switch is provided with means biasing it toward open condition. The frame is provided with a plurality of notches in which are receivable pins forming parts of the auxiliary switches. The arrangement is such that the pins are received in the notches when the frame is in its first position and the switches are in open condition but are clear of said notches when the frame is in its second position. Thus, when the main switch is in open condition, the auxiliary switches are locked also in open condition. With the main switch in closed condition and the frame in its second position, each auxiliary switch is free for change from open to closed condition. The frame is provided with a resilient stop member individual to each auxiliary switch for co-operation with a second pin forming a part of said switch to retain it in closed condition against the influence of the auxiliary switch bias. With the main switch closed and one or more auxiliary switches also closed, return of the main switch to open condition permits return of the frame from its second to its first position thereby releasing the actuated

auxiliary switches from the frame carried stop members whereupon the actuated auxiliary switches are returned to open condition under the influence of their bias and the frame becomes again effective to lock them in open condition.

5 Instead of actuation of the frame by change of the main switch from open to closed condition, the frame may be actuated by the main switch upon change from closed to open position. Likewise, the spindles may be locked in closed condition or some may be locked in closed condition and others in open condition, from which condition they may be actuated to the reverse condition after movement of the frame from its first to its second position. In any arrangement, 10 however, movement of the frame from its second to its first position effects automatic return to unactuated position of any actuated auxiliary switch.

Other objects, novel features and advantages 20 of this invention will become apparent from the following specification and accompanying drawings, wherein:

Fig. 1 is a front elevation of mechanism embodying the invention with the main and auxiliary spindles in switch-open position;

Fig. 2 is a section on the line 2—2 of Fig. 4 with the main spindle and two auxiliary spindles in switch-closed position and the third in said 25 open position;

Fig. 3 is a rear view;

Fig. 4 is an end view, and

Fig. 5 is an enlarged perspective of a detail.

On a plate 10 is slidably supported a frame 11 by pins 10a projecting through slots 11a. The frame has a window 12 and is supported for vertical movement. A spindle 13 is journaled in the plate 10 and carries an eccentric 14 which lies in the path of an extension 15 from the frame 11. 30 Springs 16 bias the frame toward the spindle 13 to maintain contact between the projections 15 and eccentric 14. The inter-engagement of the projection 15 and eccentric 14 effects reciprocation of the frame 11 upon rotation of the spindle 13 from its first position shown in Fig. 1 to its second position shown in Fig. 2. An operating button 17 is carried by the spindle 13.

Three auxiliary spindles 18 are journaled in the plate 10 and are provided with operating buttons 18a. Each spindle 13 and 18 carries an arm 19 which extends between two stops 20 and 21 serving to limit the extent of rotary movement of the spindle. Also supported by the plate 10 surrounding each spindle is a block 22 of insulating 45 material on which are mounted stationary con-

tacts 23. A disk 24 of insulating material is fixed to each spindle and carries a movable contact for co-operation with the stationary contacts 23. Each arm 19 for the spindles 18 is biased by a spring 26 toward the stop 21, and the relation of the stop members 20 and 21 for the arm 19 of the spindle 13 is such that with the arm 19 engaging the stop member 20 the frame 11 is in its first position and with the arm engaging the stop 21 the frame 11 is in its second position.

Each spindle 18 carries a pin consisting of radially extending portions 27 and 28 extending from the spindle parallel to the path of the frame 11 when the arm 19 engages the stop 20. A perpendicular projection 29 extends from the frame 11 above the window 12 and has notches 30 in which the pin portions 27 are receivable with the frame 11 in its first position. When the frame is in its second position, the projection lies beyond the ends of the pin portion 27. Below each spindle 18 the frame 11 carries a resilient member or leaf spring 31 of such design and arrangement that the pin portion 28 wipes over it when the spindle is rotated to locate the arm 19 against the stop 21 with the member 31 yielding to permit such rotation. The length of the member 31 is such that when the spindle 18 is rotated to engage the arm 19 with the stop 21, the pin portion 28 has cleared the end of the member 31 permitting the member 31 to swing into the path of the pin portion 28 to prevent return rotation of the spindle 18 under the influence of the spring 26.

With the main spindle 13 and auxiliary spindles 18 in the position shown in Fig. 1, the switches associated therewith preferably are in open condition and the auxiliary spindles are locked against rotation due to the pin portions 27 being received in the notches 30. Rotation of the spindle 13 from the position shown in Fig. 1 to the position shown in Fig. 2 moves the frame 11 from its first position to its second position thereby releasing the pin portions 27 from the notches 30 whereupon any auxiliary spindle 18 may be actuated. After actuation of an auxiliary spindle, it is latched in actuated position against the return action of the spring 26 by engagement with the pin portion 28 with the end of the member 31 as shown in Fig. 2. Any actuated auxiliary spindle will remain in actuated position as long as the main spindle is retained in its actuated position unless it is restored to unactuated position manually as above noted. However, upon return of the spindle 13 to its original position, the frame 11 moves toward its first position under the action of the springs 16 to disengage the members 31 from the pin portions 28 of actuated spindles 18 thereby permitting such spindles to return to original position under the influence of the springs 26 after which the notches 30 again receive the pin portions 27 to lock the auxiliary spindles with the frame 11 in its first position.

I claim:

1. A device of the character described comprising a main switch element movable between a first and a second position, one or more auxiliary switch elements movable between first and second positions, means common to all said auxiliary switch elements for locking them in their first positions, and means effective upon movement of said main switch element from its first position into its second position to render said auxiliary switch element locking means inoperative.

2. A device according to claim 1 and including means individual to each auxiliary switch element biasing it toward its first position, and means individual to each auxiliary switch element effective upon movement of the auxiliary switch element to its second position with the main switch element in its second position to hold the auxiliary switch element against its bias.

3. A device according to claim 1 and including means for automatically restoring said auxiliary switch element locking means upon return of said main and auxiliary switch elements to their first positions.

4. A device according to claim 1 and including means individual to each auxiliary switch element biasing it toward its first position, means individual to each auxiliary switch element effective after movement of the auxiliary switch element to its second position with the main switch element in its second position to hold the auxiliary switch element against its bias, and means for automatically moving the auxiliary switch element by its biasing means upon return of said main switch element to its first position and also release the auxiliary switch elements from their locking means and return the auxiliary switch elements to their first positions under the bias influence.

5. A device of the character described comprising a main switch element movable between a first and a second position, one or more auxiliary switch elements movable between first and second positions, a frame movable between a first and a second position, means on said frame and auxiliary switch elements inter-engageable with the frame and said switch elements in their first positions to lock them in their first positions, and means effective upon actuation of the main switch element from its first to its second position to move said frame into its second position to render inoperative said auxiliary switch element locking means.

6. A device according to claim 5 and including means individual to each auxiliary switch element biasing it toward its first position, and means individual to each auxiliary switch element effective upon movement of the auxiliary switch element to its second position with the main switch element in its second position to hold the auxiliary switch element against its bias.

7. A device according to claim 5 characterized by means effective upon return of said main switch element to its first position to restore any actuated auxiliary switch element and said auxiliary switch element locking means.

8. A device according to claim 5 characterized by means individual to each auxiliary switch element biasing it toward its first position, means individual to each auxiliary switch element effective upon movement of the auxiliary switch element to its second position with the main switch element in its second position to nullify the auxiliary switch element bias, and means biasing said frame toward its first position.

9. A device of the character described comprising a main switch element movable between a first and a second position, one or more auxiliary switch elements movable between first and second positions, a frame movable between a first and a second position, pins carried by said auxiliary switch element, notches in said frame for receiving said pins with the frame and auxiliary switch element in their first position, and

means effective upon actuation of the main switch element from its first to its second position to move said frame into its second position to disengage said notches and pins.

10. A device according to claim 9 characterized by means individual to each auxiliary switch element biasing it toward its first position, and means individual to each auxiliary switch element effective upon movement of the auxiliary switch element to its second position with the main switch element in its second position to nullify the auxiliary switch element bias.

11. A device according to claim 9 characterized by means effective upon return of said main switch element to its first position to restore any actuated auxiliary switch element and said auxiliary switch element locking means.

12. A device according to claim 9 characterized by means individual to each auxiliary switch element biasing it toward its first position, means individual to each auxiliary switch element effective upon movement of the auxiliary switch element to its second position with the main switch element in its second position to nullify the auxiliary switch element bias, and means biasing said frame toward its first position.

13. A device of the character described comprising a main switch element movable between a first and a second position, one or more switch elements movable between first and second positions, a frame movable between a first and a second position, a first pin carried by each auxiliary switch element, notches in said frame for receiving said first pins with the frame and auxiliary switch elements in their first positions,

means effective upon actuation of the main switch element from its first to its second position to move said frame into its second position to disengage said notches and first pins, a second pin carried by each auxiliary switch element, and spring members carried by said frame for engagement by said second pins upon movement of said auxiliary switch elements into second position with said frame in its second position to oppose movement of said auxiliary switch elements and after arrival of said auxiliary switch elements in their second positions to oppose return thereof to first position.

14. A device according to claim 13 characterized by means effective upon return of said main switch element to its first position to restore any actuated auxiliary switch element and said auxiliary switch element locking means.

15. A device according to claim 1 characterized by means effective upon return of said main switch element to its first position to restore any actuated auxiliary switch element and said auxiliary switch element locking means.

16. A device according to claim 5 in which the means for locking the auxiliary switch elements in their second positions consists of pins carried by said auxiliary switch elements and co-operating leaf springs carried by said frame.

17. A device according to claim 9 in which the means for locking the auxiliary switch elements in their second positions consists of pins carried by said auxiliary switch elements and co-operating leaf springs carried by said frame.
